(57) **CLAIM**

The ornamental design for a rib preparation tool with a pivot, as shown and described.

DESCRIPTION

FIG. 1 is a top front perspective view of an embodiment of a rib preparation tool with a pivot shown in accordance with our new design;

FIG. 2 is a top rear perspective view of the rib preparation tool with a pivot shown in FIG. 1;

FIG. 3 is a bottom front perspective view of the rib preparation tool with a pivot shown in FIG. 1;

FIG. 4 is a bottom rear perspective view of the rib preparation tool with a pivot shown in FIG. 1;

FIG. 5 is a front elevation view of the rib preparation tool with a pivot shown in FIG. 1;

FIG. 6 is a rear elevation view of the rib preparation tool with a pivot shown in FIG. 1;

FIG. 7 is a top plan view of the rib preparation tool with a pivot shown in FIG. 1;

FIG. 8 is a bottom plan view of the rib preparation tool with a pivot shown in FIG. 1;

FIG. 9 is a left elevation view of the rib preparation tool with a pivot shown in FIG. 1; and,

FIG. 10 is a right elevation view of the rib preparation tool with a pivot shown in FIG. 1.

The features shown in broken lines are for the purposes of showing environmental structure and form no part of the claimed design.
